Des. 225,968

Patented Jan. 16, 1973

225,968

CLOSURE CLIP FOR BAGS OR THE LIKE

Jack E. Crawford, Pittsford, Albert B. Martone, Canandaigua, and Robert H. Olson, Pittsford, N.Y., assignors to Mobil Oil Corporation

Filed Oct. 7, 1971, Ser. No. 187,587

Term of patent 14 years

Int. Cl. D8—08

U.S. Cl. D8—259

FIG. 3

FIG. 4

FIG. 1

FIG. 2

FIG. 1 is a top plan view of a closure clip for bags or the like showing our new design;

FIG. 2 is a side view;

FIG. 3 is a top plan view of a modified form of the clip shown in FIG. 1;

FIG. 4 is a side view;

I claim:

The ornamental design of a closure clip for bags or the like, substantially as shown and described.
